METHOD OF LIQUEFYING AND STORING FUEL GASES

Lee S. Twomey, Vista, Calif.

Application May 9, 1934, Serial No. 724,692

6 Claims. (Cl. 62—175)

The object of my invention is to provide means and a method for economically reducing hydrocarbon gases to the liquid condition, for maintaining them in storage at a slight superatmospheric pressure, and for converting them back to the gaseous state at such times as they may be required.

It is well known that at the present time many large cities rely largely on gas for household heating and for industrial purposes and that this gas is in large part of natural origin and is brought to the point of consumption over great distances.

The pipe lines through which this gas is conducted, often hundreds of miles in length, are enormously costly to build and to operate. The demand for gas naturally fluctuates with weather conditions, the variation between peak load and low load being in many cases as high as ten to one. As it is commercially impossible to provide an adequate amount of storage for gas at atmospheric temperature and pressure, or even for gas compressed to a fraction of its original volume, it has been necessary to adopt one or the other of two alternatives: either to provide production, pipe lines, and pumping facilities having a normal capacity adequate for normal loads, crowding these lines to their limit during times of peak load and often leaving an excess demand un supplied, or to so proportion the production and transportation facilities as to provide for maximum load, with the result that a very large investment is standing idle the greater part of the time.

Further, in most oil fields gas flow is utilized as a means for producing or is concomitant with the production of petroleum, and as the daily output of wells is limited by law or agreement and the wastage of gas is forbidden, a reduction in the demand for gas often results in a direct loss of allowable oil production. From the standpoint of the oil producer it is highly desirable that the requirement for gas be the same throughout the seasons.

My proposal is to operate pipe lines conducting gas in the most economical manner, at their normal load constantly maintained, to reduce the excess delivery during periods of low load to the liquid form, to maintain this liquefied gas in storage at substantially atmospheric pressure, and to draw on this liquid storage during peak load periods. By this procedure, which is made possible by the methods herein disclosed, existing lines may be made to transport much greater quantities of gas throughout the rotation of sea-

sons than is now possible, the excessive cost of pumping at maximum pressure during peak load periods is avoided as is also acute shortage during times of extreme cold, and new installations of pipe lines and pumps may be based on average annual loads rather than on the maximum seasonal load.

It is now common practice to store limited quantities of fuel gas in pressure vessels, at from 100 to 500 pounds' gauge. When it is reflected that any unit of space will hold approximately eight volumes of gas compressed to 100 pounds gauge or thirty five volumes compressed to 500 pounds, while it will hold approximately six hundred and forty volumes of the same gas when reduced to liquid form, and further that the liquid gas does not necessarily require the use of pressure vessels, the extreme advantages incident to storage in the liquid phase will be evident.

Natural gas, while quite variable in the proportions of its constituents, is qualitatively constant, being composed in almost all cases of varying proportions of the first four members of the normal series of paraffins—methane, ethane, propane, and butane. The pentanes and other constituents which may profitably be put into commercial liquid products are now, as a rule, closely fractionated from the constituents normally gaseous, and sold with the gasoline which accompanies most gas produced from oil wells.

The temperatures and pressures at which hydrocarbon fuel gases may be liquefied will vary from place to place and from time to time with the quantitative composition of the gas delivered by any pipe line. The plant in which it is reduced to the liquid state must therefore be reasonably flexible as to both temperature and pressure possibilities, but should in any case be capable of liquefying pure methane, which is the most refractory constituent of most natural gases. The required plant will have apparatus for liquefying and suitable vessels for storage without waste, the latter being provided with means for withdrawing the liquid and for re converting it to the gaseous form without fractionating it by evaporation of its lighter constituents.

The method steps making up my invention are best described in connection with the attached drawing, which diagrammatically illustrates various combinations of apparatus suitable for putting them into effect.

In the following description all temperatures are in degrees Kelvin, or centigrade degrees absolute. Pressures stated in atmospheres are ab-

solute, those given in pounds gauge are plus one atmospheric absolute.

Referring to the drawing: 10 is a receiver containing a quantity of liquefied anhydrous ammonia, at atmospheric temperature and under a pressure equivalent to its vapor pressure at that temperature. The liquid ammonia passes through pipe 11 and a regulating valve 12 to the shell (the space surrounding the tubes) of a condenser 13, the shell being maintained at or about atmospheric pressure by regulation of the valve. In this shell the ammonia vaporizes at an initial temperature about 240°, being its boiling point at atmospheric pressure. Absorbing heat from gaseous ethylene flowing downwardly through the tubes of condenser 13, the ammonia gas leaves the shell through pipe 14 at substantially atmospheric temperature. Passing then to compressor 15, it is raised to its condensation pressure at atmospheric temperature, then through pipe 16 to and through the tubes of a condenser 17, these tubes being cooled by water. In the condenser it is brought back to substantially atmospheric temperature and thereby condensed, the liquefied ammonia passing through pipe 18 to receiver 10. This completes a closed ammonia cycle.

Numeral 19 indicates a receiver containing a quantity of liquefied ethylene, at a temperature about 240° and at a pressure corresponding to its vapor pressure at that temperature. The liquid ethylene passes through pipe 20 and a regulating valve 21 to the shell of a condenser 22, the shell being maintained at or about atmospheric pressure by regulation of the valve. In this shell the ethylene vaporizes at an initial temperature about 168°, being its boiling point at atmospheric pressure.

Withdrawing heat from partly cooled fuel gas flowing downwardly through the tubes of condenser 22, the gaseous ethylene leaves the shell through pipe 23 at substantially atmospheric pressure and flows to a group of the tubes of a dehydrating interchanger 24 in which it is heated to atmospheric temperature in cooling compressed fuel gas.

Passing then through pipe 25 to compressor 26 it is raised to its condensation pressure at the temperature of the ammonia cooled tubes of condenser 13. From the compressor the hot compressed gas flows through pipe 27 and the tubes of a cooler 28 which is supplied with cold water. In cooler 28 the compressed gas is returned to atmospheric temperature but is not liquefied, the compressed and cooled gas flowing through pipe 29 and the tubes of condenser 13 which, as already stated, are cooled by evaporating ammonia to 240°. At this temperature the ethylene condenses and passes through pipe 30 to receiver 19, thus completing the ethylene cycle.

A continuous stream of the fuel gas to be liquefied is introduced to the system through a pipe 31, which may be the pipe line through which gas is brought from the field and which may extend to connect with the distribution system as a pipe 32, a regulating valve 33 being interposed to maintain a substantially constant but usually slight pressure in the intake pipe 34. This pipe conducts the gas stream to the suction side of a compressor 35 by which it is raised to a pressure at which it will condense at a temperature of 168°. The hot compressed gas passes through pipe 36 and the tubes of a cooler 37 which is supplied with cold water. In this cooler the compressed gas is returned to atmospheric temper-

ature but is not liquefied, the compressed and cooled gas flowing through pipe 38 either to the shell of a dehydrating interchanger or to a device for scrubbing out the major part of any carbon dioxide which may be present in the fuel 5 gas.

The scrubber consists of a tower 39 arranged to collect a pool of water 40 in its lower end. A pump 41 draws a stream of this water through pipe 42 and discharges it through pipe 43 into 10 the lower end of a tubular interchanger 44. A chamber 45 above the upper tube sheet in the tower permits the escape of carbon dioxide evolved from the saturated water when it is heated as by a steam coil 46. A vent valve 47 15 permits the escape of this gas when it reaches system pressure. A float valve 48 governs the height of the water pool 49 and permits a stream of hot water to pass through pipe 50 to the upper end of the space around the tubes. Passing 20 downwardly through the shell the hot water counterflows the upflowing cold water within the tubes and passes through pipe 51 to a hose nozzle or other spraying means 52 at atmospheric temperature and at system pressure. 25

The gas leaving cooler 37 through pipe 38 enters the bottom of the spray tower and flows upward in counterflow to the descending water streams and passes from the upper end of the tower through pipe 53 to dehydrating interchanger 24. To bypass the scrubbing unit in case its use should not be necessary or desirable a crossover pipe 54 and diversion valves 55 and 56 are provided.

In this interchanger the fuel gas is cooled, by cold ethylene gas and by gas returned from farther on in the system, to a temperature at which water vapor is condensed and in large part frozen. It should be provided with baffles 57 by which it is divided into pockets, these pockets being drained 40 by valves 58. The entire unit should be duplicated and provided with suitable diversion pipes and valves so that one may be cut out of the system and freed from ice while the other is being used. 45

From the dehydrator the partly cooled gas passes through pipe 59 into the tubes of condenser 22 which, as said, are cooled by liquid ethylene evaporating at atmospheric pressure at 168° K. In this condenser the entire gas liquefies 50 unless it contains hydrogen or nitrogen which, if present, may be separated in later elements of the apparatus. Any carbon dioxide which may be present in the original gas and is not removed in the scrubber is frozen at the temperature existing in this condenser but is not deposited in the tubes because of the rapid flow of liquid hydrocarbons over them, and the entire condenser output, consisting of liquid hydrocarbons, suspended solid carbon dioxide, and gaseous nitrogen and 60 hydrogen, passes through pipe 61 to the trap 62.

The trap which, like the dehydrator, should be provided in duplicate to permit of thawing when choked, is a vertically arranged shell into which pipe 61 enters at a medial height. Above 65 this level a filtering disc 63 is disposed across the shell, this disc being of cloth supported by a perforated plate or of fine mesh metal filter cloth or other known filtering material. Carbon dioxide crystals entering with the liquefied gas 70 may settle into the lower part of the shell from which they may be withdrawn as a slimy suspension through valve 64, or they may pass upwardly with the liquid and be retained by the screen. The liquid and gaseous portions of the 75

stream pass through the screen and through pipe 65 to the tubes of an interchanger 66.

The pressure in the various receivers, using the refrigerating gases above described will be approximately 110 pounds gauge in ammonia receiver 10 and approximately 250 pounds gauge in ethylene receiver 19. The pressure in the trap will vary with the constitution of the particular gas, but if we assume the gas to consist entirely of methane, which is an extreme condition, it will be about 290 pounds gauge. With most natural gases the pressure will be materially lower. All the above temperatures assume perfect interchange, which is hardly realized, and in practice the outlet temperatures will usually be about 5° above those stated.

The above described method of cooling and liquefying gases is substantially that described and claimed in my copending application entitled "Method of producing low temperature refrigeration", filed May 9, 1934, under Serial No. 724,691.

As fully set forth in the copending application, any one of a number of other gases may be substituted for ammonia in the first cycle, as for example propylene, propane, allylene, methyl chloride, sulphur dioxide, and carbon dioxide, while ethane and nitrous oxide may be substituted for ethylene in the second, all these changes involving some changes in temperatures and pressures. It is also possible to raise and lower the evaporating temperatures of the refrigerant gases by varying the pressure to which they are expanded. Air cooled apparatus may be substituted for the water cooled units 19, 32, and 41, and other changes in structure and operation may be made without departing from the spirit of the disclosure.

As above described, the product (liquefied fuel gas) continuously passes into trap 62 at a temperature approximating 168° absolute and a pressure ranging downward from 290 pounds gauge. As it would be unduly expensive to store the liquid under such conditions of temperature and pressure, I first reduce its temperature to that at which its vapor pressure is only slightly superatmospheric, preferably not in excess of 15 pounds gauge. If the liquid fuel gas should consist solely of methane, the temperature at 15 pounds gauge would be 122°, but in practice it will usually be somewhat higher.

To accomplish this result I permit a portion of the liquefied gas to evaporate and expand either to atmospheric pressure, at which pressure methane will be reduced to 112°, or to the pressure at which it is to be stored.

The liquid and gaseous products flow together from the trap through pipe 65 and the tubes of an interchanger 66, in which its temperature is somewhat reduced as will be described. Thence the liquid flows through pipe 67 and valve 68, by which the pressure is reduced, into a storage tank 69 so proportioned as to have a safe working pressure of say 15 pounds gauge. This tank should be provided with a blow-off pipe 70 having a safety valve 71 set for a pound or two over working pressure, but this valve is provided for emergencies only.

The pressure on this tank may be read on a pressure gauge 72 and should be maintained at the working pressure by manipulation of a valve 73 in a return gas line 74. This valve may conveniently be a weighted or spring relief valve set for the working pressure.

On the passage of the liquid product through control valve 68 into the zone of lower pressure

within storage tank 69 a portion of the liquid will flash into the gaseous form and the temperature will be reduced to the boiling point of the liquid at the pressure within the tank. The portion which does not so flash and return to the gaseous condition is stable at tank pressure so long as leakage of heat into the tank is prevented. It may be said at this point that all parts of this apparatus which are materially below atmospheric temperature are heavily heat insulated, but as this practice is entirely conventional, it need not be described in detail.

It should be observed that the tank pressure of 15 pounds above mentioned is suggestive only, being a rather desirable mean between the very low temperature required to maintain the liquid stable at atmospheric temperature and the heavy apparatus required to store at compression pressure. It will be obvious, however, that a large part of the advantages of the invention would accrue to the use of any pressure within the limits of the compression, provided always that the temperature maintained in the storage vessel be below the critical temperature of the liquid and not substantially above the boiling point of the liquid at whatever pressure may be applied.

The gas produced by the above described flashing operation leaves the tank through pipe 74, at the temperature of the liquid in the tank, and is thus materially colder than the fluids passing through interchanger 66. To recover the cooling effect of this relatively large volume of cold gas I pass it back through a series of interchangers already referred to: thus it passes through pipe 74 to the shell of interchanger 66 where it somewhat reduces the temperature of the fluid stream leaving trap 62, then through pipe 75 to one of the tube groups of the dehydrating interchanger 24, where it is brought back to atmospheric temperature, and finally returns through pipes 77 and 34 to the intake side of the fuel gas compressor. If this vent gas contains any material proportion of hydrogen or nitrogen, it may be preferable to return it to distribution pipe 32 through crossover pipe 78, diversion valves 79 and 80 being provided for that purpose.

The liquefied fuel gas being now in storage at a preferred superatmospheric pressure and at a temperature at which its vapor pressure does not exceed the preferred storage pressure, it is necessary to maintain it at that temperature so long as it is stored, and as even the most effective insulation will permit some infiltration of atmospheric heat toward the storage vessel, it becomes necessary to constantly withdraw this heat either from the stored contents or from a fluid layer interposed between the vessel itself and the interior of the insulation.

The first of these alternatives is shown in the drawing as a pipe coil 81 sealed into the upper portion of the vessel and supplied with a liquefied gas such as methane. The interior of the coil is maintained at a pressure below that of the liquefied refrigerant and the evaporation of this liquid as it is admitted through control valve 82 reduces the temperature of the coil below the temperature of the stored liquid and thus provides for absorption of the heat which passes through the insulating layer into the liquefied contents of the vessel. The supply of liquid is shown as being drawn through a pipe 83 from a source of liquid of the same or lower boiling point, which will be described.

The second of these alternatives is shown in the drawing as a jacket 84 surrounding the vessel

and spaced a few inches from it, this jacket being gas tight at atmospheric pressure. The liquefied cooling gas is admitted to this jacket through a valve 85, in such quantity as to maintain at least a small pool of liquid in the jacket, which is maintained at atmospheric pressure. This liquefied gas is regasified at a rate determined by the rate of heat infiltration, and maintains around the vessel a temperature slightly below the normal storage temperature, thus preventing atmospheric heat from reaching the stored contents. The gas thus produced in either the coil or the jacket passes through pipe 86 into the system by which it is produced, to be reliquefied. While not functionally identical, these two methods for maintaining the stored liquids at a stable temperature are practically equivalent.

The figure shows a standby plant for supplying this cooling liquid which is, in its essential features, a replica in miniature of the liquefying apparatus already described. In this standby plant 87, 88, and 89 are receivers for respectively ammonia, ethylene, and methane, 90 is an ethylene condenser cooled by evaporating liquid ammonia, 91 is a methane condenser cooled by evaporating liquid ethylene, 92, 93, and 94 are compressors for respectively ammonia, ethylene, and methane, 95, 96, and 97 are water cooled condensers for removing the heat of compression from the same gases, and 98, 99, and 100 are interchangers. The liquid methane collecting in receiver 89 passes through interchanger 100 and thence through pipe 83 to valve 82 through which it is admitted to the expansion coil 81 or to valve 85 by which it is admitted to jacket 84. In either case the expanded gas returns to the suction side of compressor 94 through pipe 86 to methane interchanger 100, then through pipe 101 to ethylene interchanger 99, through pipe 102 to ammonia interchanger 98 and finally through pipe 103 to the suction of methane compressor 94, at substantially atmospheric temperature and pressure.

The object in maintaining even a slight superatmospheric pressure on tank 52 is to provide a heat head between the contents of the tank and a liquid of the same boiling point expanding to atmospheric pressure. By expanding the cooling liquid to a slightly subatmospheric pressure, or by using a cooling liquid of lower boiling point, the requirement for pressure on the tank contents may be avoided.

On the other hand it may be economically desirable to store the liquid product at much higher pressures, as from 100 pounds to 400 pounds gauge, in which case the initial pressure on the gas is increased and the condensing temperature is correspondingly raised. At 100 pounds gauge the boiling point of methane is 142° K., at 400 pounds it is 171° K., and at these temperatures the heat head between the atmosphere and the contents of the tank is materially lowered, with a consequent reduction in the amount of refrigeration required to maintain a constant temperature within the tank. At 400 pounds pressure the cooling may be effected by the atmospheric pressure evaporation of liquid ethylene.

In returning stored gas into the distribution system it is necessary to supply the heat rendered latent in evaporation and for returning the gas to atmospheric temperature. For this purpose a device is provided comprising a shell 109 into which liquefied gas passes from storage vessel 69 through pipe 104 controlled by a valve 105, the gasified material flowing from the upper part 75 of the shell through pipe 106 into distribution

pipe 32. If the pressure in the tank is below that of distribution, the liquid may be pumped into the gasifying device. The requisite heat is supplied by steam or other heating fluid admitted into the space around the tubes through a pipe and valve 107 and the space may be drained by means of a pipe and valve 108.

I claim as my invention:

1. The method of liquefying and storing hydrocarbon fuel gas which comprises: raising a stream of said fuel gas to a material superatmospheric pressure; effecting a first cooling of said fuel gas stream to substantially atmospheric temperature; effecting a second cooling of said stream to a temperature below the freezing point of water whereby said stream is substantially dehydrated; effecting a third cooling of said stream by heat interchange against an evaporating liquid refrigerant to a temperature at which the hydrocarbon constituents thereof are liquefied at compression pressure; effecting a fourth cooling of said stream; introducing said stream into a storage vessel maintained at a desired subatmospheric temperature, and passing any fuel gas evolved in said vessel in heat exchange relation with said stream successively through said fourth and second cooling effects.

2. In the storage of liquefied hydrocarbon fuel gases at temperatures materially below atmospheric, the step of evaporating a liquid refrigerant in heat interchange relation with said liquefied hydrocarbon in a zone substantially surrounding a stored body of said liquefied hydrocarbon, and circulating and reliquefying said refrigerant in a closed cycle.

3. In the production and use of liquid methane as a refrigerant, the steps comprising: liquefying a stream of compressed gaseous methane by heat interchange against a stream of evaporating liquid ethylene; liquefying said ethylene stream under pressure by heat interchange against a stream of evaporating anhydrous liquid ammonia; liquefying said ammonia stream by cooling under superatmospheric pressure, evaporating said liquid methane stream under less than its compression pressure in heat exchange relation with an object to be cooled; passing the evaporated methane in heat exchange relation successively against said liquid methane, ethylene, and ammonia streams, whereby said streams are cooled below their respective liquefying temperatures, and returning the gaseous methane at substantially atmospheric temperature to be recompressed.

4. The method of introducing a stream of liquefied gas under pressure into a storage vessel maintained at a lower pressure which includes the step of cooling said stream to a temperature of stability at vessel pressure by the partial evaporation of said stream on the introduction of said stream into said vessel and by heat interchange between said stream while at compression pressure and the cold gases produced by said evaporation.

5. In the storage of liquefied hydrocarbon fuel gases at temperatures materially below atmospheric, the steps comprising: evaporating liquid methane in heat interchange relation with said liquefied hydrocarbon; circulating and reliquefying a stream of said methane in a closed cycle by compression and heat interchange of said methane against a stream of evaporating liquid ethylene; liquefying said ethylene stream under pressure by heat interchange against a stream

of evaporating anhydrous liquid ammonia; liquefying said ammonia stream by cooling under superatmospheric pressure, and cooling each of said streams to a point below its liquefying temperature and after liquefaction by heat inter-change against a stream of said evaporated methane.

5 6. The method of transmitting and distribut-ing a fuel gas which comprises: liquefying the

portion of the gas delivered through the trans-mitting line in excess of the momentary demand of the distributing system for said gas; storing said liquefied gas in the liquid condition; gasi-fying said liquefied gas at times of increased de-mand, and delivering said gas to the distribut-ing system.

LEE S. TWOMEY.
